UNITED STATES PATENT OFFICE.

JOHN A. PILCHER, OF ROANOKE, VIRGINIA.

BRAKE ARRANGEMENT FOR SIX-WHEEL TRUCKS.

1,095,594.

Specification of Letters Patent.

Patented May 5, 1914.

Application filed August 16, 1913. Serial No. 785,144.

To all whom it may concern:

Be it known that I, JOHN A. PILCHER, a citizen of the United States, residing at Roanoke, in the county of Roanoke and 5 State of Virginia, have invented certain new and useful Improvements in Brake Arrangements for Six-Wheel Trucks, of which the following is a specification.

The object of this invention is to provide 10 a simple and efficient means for the operation of the brakes on six wheel trucks for railway cars, with which object in view it consists of the arrangement and combination of parts as herein described and claimed.

15 In the drawings, Figure 1 represents in plan view a truck with my invention applied, Fig. 2 is a longitudinal cross section taken on the line A B, Fig. 1, and Fig. 3 an end elevation of the same.

20 Referring to the drawings in which like parts are similarly designated, wherever they occur, 1 represents the bolster of a six wheel truck, 2 the side frames of the same and 3—4 and 5 the pairs of wheels on their 25 respective axles. The brake beams 6—7 and 8 are hung from the side frames 2 or from some other suitable part in the customary manner by means of U-shaped hangers 9 which are pivotally connected to the side frames at 30 10—11 and 12, and the brake heads 13, which are secured to the beams in any of the customary manners, are hooked over the U-shaped hangers at the bottom. The brake shoes 14 are keyed to the heads 13 in the 35 usual way.

The brake beam 7, which is intended for use in braking the wheels 4 is actuated by means of a dead lever 15 which is permanently fulcrumed at a point 16 to some suitable part of the truck. This point 16 is at the lower extremity of the lever 15. Between the extremities of the lever 15, at 17, the brake beam 7 is pivotally connected to the lever 15. A pull rod 18 is pivotally connected to the upper extremity of the dead lever 15 at 19 in such a manner that a pull in the rod 18 will force the brake shoes of the beam against the wheels 4. The other end of the pull rod 18 is pivotally connected at 20 to the upper extremity of a floating lever 21, to which lever is pivotally connected between its extremities at

22 the brake beam 6 for the wheels 3. To the lower extremity of the floating lever 21 is pivotally connected at 23 a pull rod 24 which is so arranged that a pull in this rod will force the shoes 14 of the brake beam 6 up against the wheels 3, and the floating lever 21, then fulcruming about 22, will apply the brakes to the wheels 4 through the pull rod 18. The opposite end of the pull rod 24 is pivotally connected at 25 to the lower extremity of a live lever 26 to which is pivotally connected, between its extremities, at 27, the brake beam 8 for the wheels 5. To the upper extremity of the live lever 26 is pivotally connected at 29 a pull rod or other tension member 30 which is actuated from the braking means on the car body. The live lever 26 is so arranged that a pull in the rod 30 will force the shoes 14 of the beam 8 up against the wheels 5, and the live lever 26, then fulcruming about 27 will pull on the rod 30 and apply the brakes on the other two pairs of wheels as already described. It should be noted that the same results will be attained if the pull rod 30 is attached to the opposite end of the system of levers at 16 and the permanent fulcrum be transferred from 16 to 29, in which case the lever 15 becomes the live lever of the system and the lever 26 becomes the dead lever.

By correctly proportioning the various levers, a perfect equalization of the braking power will be obtained among the three pairs of wheels.

Having thus described my invention, what I claim is,

In a brake arrangement for six wheel trucks the combination of a dead lever fulcrumed at one extremity, a brake beam pivotally connected to said dead lever between the extremities thereof, a tension member pivotally connected at one end to the other extremity of said dead lever, a floating lever to which is pivotally connected at one extremity the other end of the said tension member, a second brake beam pivotally connected to said floating lever between the extremities thereof, a second tension member pivotally connected at one end to the other extremity of said floating lever, a live lever to which is pivotally connected at one ex-

tremity the other end of said second tension member, a third brake beam pivotally connected to said live lever between the extremities thereof, and means for actuating 5 the other extremity of said live lever from the brake mechanism of the car body, substantially as described.

In testimony whereof I affix my signature in presence of two witnesses.

JOHN A. PILCHER.
